UNITED STATES PATENT OFFICE

HARLEY J. MEGLEY, OF CHICAGO, ILLINOIS

PRINTING MEANS

Application filed December 7, 1929. Serial No. 412,316.

This invention relates to printing means adapted for use with multigraph or other rotary or drum type printing machines and also adapted for use with flat plates or base members for use on standard flat bed presses.

As well known in the art, the slugs which are used on flat bed presses without base plates are known as "type high" slugs. Where I use the expression herein "less than type high", I refer to slugs which are of a height less than the height of the slugs above referred to and particularly to slugs adapted for use with multigraph or other rotary or drum type printing machines or which are combined with flat base plates or carriers when used on standard flat bed presses.

In my prior patents, No. 1,461,927 of July 17, 1923, and No. 1,601,221 of September 28, 1926, I have provided for forming integral lines of type or type slugs of a height less than "type high" and for forming retention means in these slugs for cooperation with the chases, undercut rails or other retention means in or on the cylinder, drum, flat base plate or other type carrier.

The present invention relates to binding or tying type slugs which are less than "type high" and which are provided with suitable retention means together to form unitary printing plates or combinations adapted for mounting as a unit upon the carrier whether it be a curved surface drum or a flat base plate by the simple expedient of engaging the retention means in the slugs with the retention means in or on the carrier and sliding the unit into place in a direction longitudinally of the slugs. So far as the present invention is concerned, the particular formation of the slugs and the particular character of the retention means may vary, it being understood that the present invention is suitable for use with the slugs disclosed in my prior patents above referred to and that the slugs of these prior patents are, therefore, illustrative of any suitable slugs with which the present invention is or may be found suitable.

By the provision of slugs which are less than "type high" with retention means for securing them to the drum, flat base plate or

other carrier, the tedious formation, setting up and use of separate nicked blocks, one for each letter or other character, has been greatly simplified and the printing matter may be placed upon the carrier in unitary printing 55 lines.

Within the scope of the present invention, the less than "type high" slugs may be formed with printing characters, such as letters or figures, or with printing rules or with symbols or other printing means or any desired combination thereof. These slugs may also be formed without any printing means thereon, serving in such a case as tie members for the strips which are arranged across the same. The cross strips tie a number of the less than "type high" slugs into a unitary assembly, 60 making a plate which is of a unitary nature and which is, at the same time, flexible, that is, the parts of the plates are all separable to permit readily changing any desired part or bringing any desired combination of slugs and cross elements together. In other words, 65 any slug or any number of slugs may be removed and replaced with others. In a plate, in which the parts are all integral, this is impossible without cutting out one part and replacing it with another, which is impracticable. At the same time, once a number of the less than "type high" slugs and cross members are tied together, the manner of again 70 assembling them and individually mounting the separate slugs upon the carrier, to run off further copies of the same printed matter, is entirely eliminated. The cross members are adapted for retaining the desired assembly which is adapted for replacement upon the carrier as a unit at any time and without again assembling the slugs or individually securing them to the carrier. The 75 cross members are particularly adapted to be formed and used as printing rules, but it is to be understood that the particular printing character of these cross members may be varied and may even be omitted within the scope 80 of the present invention.

The cross members serve as ties for the less than "type high" slugs and the less than "type high" slugs serve as ties for the cross members. Where it is desired to print generally 100

vertical lines for columns or tabular work, the cross members of the present invention are preferably in the form of printing rules disposed generally circumferentially of the drum, or, where the carrier is in the form of a flat base member or plate, these cross members are disposed over the surface of this flat plate across the direction of extension of the slugs and, in either case, are provided with raised printing rules or edges for printing the vertical lines. In this case, the unitary character of the less than "type high" slugs will maintain the desired relative positions of the cross members, not only when the cross members are in place upon the carrier, but will maintain that positioning upon removal of the assembled slug and cross member unit from the carrier so that this unit may be replaced without again effecting the desired relationship of the slugs and cross members.

According to the present invention, the less than "type high" slugs are, preferably, grooved generally transversely across the tops of the slugs. I am aware that cross grooves have been provided in the upper ends of "type high" slugs and that tie members have been secured therein, but these provisions have been in connection with "type high" slugs for tabular work and the cross grooves have been confined to the raised printing rules upon the upper ends of the slugs. That is, the lower ends of the grooves have terminated at the base of the printing rule projection and the cross members have, therefore, seated directly upon the upper ends of the slugs with the result that there is not a true base for the cross members and these cross members will not be true if there is any variation in the heights of the slugs or any irregularity in the upper surfaces thereof. In the present invention the cross grooves extend through the depths of the upper flanged heads of the slugs. When the slugs are positioned upon the carrier, the inner or lower ends of the grooves preferably extend inwardly to or inwardly beyond the surface of the carrier so that the cross members, upon insertion through these grooves, will rest and find support not upon the slugs themselves, but upon the outer surface of the drum or flat base plate. Where the slugs are provided with printing rules, and assuming that it is desired to print lines or other matter with the cross members, the grooves extend through the rule projections on the slugs so that the line printing edges upon the cross members may extend out to the printing edges of the rule projections on the slugs.

While the grooves and cross members are illustrated as of generally V-shaped formation with the apices presented outwardly, it is to be understood that other equivalent formations are contemplated within the scope of the present invention.

With the present invention, it is unneces-

sary to block up a solid mass of slugs in the manner required with the "type high" slugs and cross rules as previously provided. I believe that it is broadly new to interlock either a rule or binder with the slugs and to support the rule or binder upon the drum, flat base plate or other carrier for the slugs.

So far as this aspect of the invention is concerned, it is immaterial whether the surface of the carrier is circular, as in a drum type printing machine, or flat for use on standard flat bed presses. The supporting of the rules or binders which extend across the slugs upon the carrier avoids any objectionable results where there are variations or inequalities in the slugs and, at the same time, the slugs may be spaced apart with relatively wide gaps therebetween. Unless, of course, it is desired to fill in the spaces with rules or other printing material, there need be only a few slugs at spaced intervals for binding the cross members together. The present invention enables disposing printing characters on the slugs up close to the rules or binders which extend across the slugs. The bases of the rules or cross binders may be just as wide, or even wider, than heretofore, but, due to the extension of these bases down through the flanged heads of the slugs, the width of the rules or binders at the outer printing surfaces of the slugs may be less and the letters or other printing matter upon the slugs may therefore be brought up closer to the rules or binders.

The invention is illustrated in the accompanying drawings, in which:—

Fig. 1 is a plan view of a printing drum showing a printing assembly embodying the present invention in position thereon;

Fig. 2 is a fragmentary end view partially in section;

Fig. 3 is an enlarged fragmentary detail section taken on the line 3—3 of Fig. 1;

Fig. 4 is a fragmentary detail section taken on the line 4—4 of Fig. 3;

Fig. 5 is a fragmentary section taken on the line 5—5 of Fig. 4;

Fig. 6 is a fragmentary plan view showing the slugs spaced circumferentially with empty drum chases between them;

Fig. 7 is a view similar to Fig. 3 and taken on the line 7—7 of Fig. 6;

Fig. 8 is a fragmentary perspective view of a rule slug embodying the present invention;

Fig. 9 is a fragmentary perspective view of a slug binder embodying the present invention and formed with a printing rule edge;

Fig. 10 is a fragmentary perspective view of a printing rule assembly embodying the present invention and in which the slugs are spaced apart;

Fig. 11 is a fragmentary perspective view of another printing assembly embodying the

present invention in which the slugs are arranged close together and provided with printing characters with the binder strips extending across the same functioning as binder strips only and without any extending printing rules;

Fig. 12 is a view similar to Fig. 7, but showing the slug and binder assembly in connection with a flat base plate for use on a flat bed press;

Fig. 13 is a view similar to Fig. 11, but showing the binder strip provided with a printing rule edge and showing another manner of providing horizontal rules without skipping spaces in the carrier; and

Fig. 14 is another modification in which short separate grooved blocks are mounted in the chases of the carrier for holding the rule formed by the slug binder strip.

Referring to the drawings, and particularly to Figs. 1 to 7, 5 designates the drum or carrier, such as comprises part of a multi-graph or other rotary printing machine. These drums 5 are usually composed of drum segments which are usually held together by spring clips or other suitable connecting means. The drum 5 has spaced parallel rails 6 extending longitudinally thereof with the under-cut channels 7 for receiving and engaging the base flanges 8 of the type lines or slugs 9. The drum shown is of the usual known character and is merely illustrative in the present disclosure.

For purposes of illustration, I have selected the less than "type high" slugs of my prior patents above referred to for disclosure herein. As illustrated in Fig. 8, these slugs have the upper flanged heads 10 with the base flanges or base portions 8 integrally connected therewith through the connecting necks 11.

The height h (Fig. 8) of the slugs 9 is less than "type high" as that expression is understood in the art. The outer face of the head 10 carries the printing means, which printing means may be in the form of integral outwardly tapered and relatively sharp edged printing rules 12 (Fig. 8). Instead of printing rules 12, the heads 10 of the slugs 9 may carry printing characters in the form of letters as indicated at 14 in Fig. 1, or figures as indicated at 15 in the figure, or any other printing characters or symbols or combination thereof.

It is also contemplated within the present invention to omit the printing means entirely from the slugs and to use slugs of integral line formation or even individual blocks for interlocking with rule strips embodying the present invention.

The longitudinal grooves or nicks 16 formed in the opposite sides of the slugs 9 interlock with the outer headed ends 17 of the drum rails 6, as shown in Fig. 2, Fig. 3 and

Fig. 5, and hold the slugs 9 in place upon the carrier.

In the embodiment illustrated in Figs. 1 to 13, the slugs 9 are integral from end to end and in the form of unitary printing lines. 70 These slugs 9 are provided with aligned grooves 20 extending across the slugs and through the depths of the upper flanged head 10. When the slugs are positioned upon the carrier, the inner or lower ends of the grooves 75 20 preferably extend inwardly to or inwardly beyond the surface of the carrier as indicated in dotted lines at 21 in Figs. 3 and 4, so that the cross members or binder elements 22 will rest and find support upon the 80 surface of the carrier.

The binder or tie strips 22 have flat bases for seating upon the outer surface of the carrier and the portions of these strips 22 within the height of the head 10 of the slug are 85 of a cross section conforming with the shape of the grooves 20. In the illustrated embodiments of the invention, the sides of these grooves are tapered with the grooves converging outwardly so as to interlock with 90 the corresponding section of the strips 22. The strips 22 are preferably of brass, although this may vary.

Where the carrier is in the form of a drum, the binder elements 22 are disposed generally 95 circumferentially of the drum and are curved to conform with the surface of the drum as shown in Figs. 2 and 7, but, of course, where the slugs are used with a flat base plate or carrier, for use upon a flat bed press, this 100 curvature of the strips 22 may be omitted and the straight strips will seat upon the outer flat surface of the carrier as shown in Fig. 12.

Where the binder elements 22 are adapted for printing lines generally vertically with reference to the copy, their outer edges have relatively sharp edged printing rules which extend from the outer surfaces of the heads 10 for printing co-operation with the paper or other material. The binder strips 22 are 110 adapted to be inserted endwise through the aligned grooves 20 in the slugs 9 and are held against displacement outwardly from the carrier by the outwardly converging formation of the grooves and the corresponding 115 section of the binder elements. Other equivalent binder elements and groove formations which will hold the parts together in an equivalent manner are contemplated within the present invention. The binder elements 22 120 preferably have relatively tight fit in the grooves 20 so that the slugs 9 will not slip or move appreciably along the strips 22, even when the printing unit is removed from the carrier.

From the foregoing, it will now be apparent that the binder strips 22 tie or bind the printing lines or slugs 9 together to form a unitary printing plate or combination which is adapted for mounting as a unit upon the 130

carrier by the simple expedient of engaging the retention means in the slugs 9 with the cooperating retention means in or on the carrier and sliding the unit into place longitudinally of the retention means. When the printing assembly is in place, the bases of the binder strips 22 seat upon the outer rail surfaces of the carrier so that the seating of these binder strips is independent of variations or irregularities in the slugs and, at the same time, the necessity for blocking up a solid mass of slugs is avoided.

In Fig. 10 a portion of a slug and binder strip assembly embodying the present invention is shown removed from the drum. Obviously, the binder strips 22 retain the desired assembly of the slugs 9 and the entire unit is adapted for replacement upon the carrier as a unit at any time and without again assembling the slugs or individually securing them to the carrier in the desired relationship. Relatively wide spaces are shown between the slugs 9, such as obtained by skipping spaces between the slugs as shown in Fig. 7 and, at the same time, the engagement of the binder strips 22 in the slug grooves 20 holds the slugs in proper relation. The relatively tight fit of the strips 22 in the slugs will hold the slugs in substantially any desired spaced relation, but even if there is some slipping of the slugs along these strips, that is not objectionable, because the slugs are all held in assembled relation and may be conveniently slipped along the strips 22 for insertion into the desired chases of the drum or flat plate carrier.

At the same time with the unitary type line or rule formation of the printing slugs as distinguished from the individual printing characters or printing blocks or blank blocks, the desired relative positions of a number of printing rules 22' may be maintained relative to the slugs 9 and relative to each other upon removal of the assembled unit from the carrier, so that when this unit is replaced the desired rule relationship will be provided without again effecting it.

Integral slug lines 30 may be inserted into the chases of the carrier adjacent the ends of the printing units as shown in Fig. 1 for holding the rule or tie strips 22 against displacement in a direction longitudinally of said strips. The slugs 30 may have printing characters or printing rules or other symbols or combination thereof, or these slugs 30 may be blank slugs for the sole purpose of providing stops at the ends of the printing assembly to prevent endwise displacement of the strips 22.

In Figs. 1, 2, 3 and 5, the slugs 9 are placed adjacent each other in adjacent chases of the carrier and some of the slugs 9 have printing rules, while others have printing characters.

In Figs. 6 and 7, the assembly is substan-

tially the same as Figs. 1 and 2, but in this case the slugs 40, instead of being placed adjacent each other in adjacent chases of the carrier, are spaced apart so that there will be empty chases between the spaced slugs 40. These slugs 40 may, as before, be blank slugs for holding the strips 42, or they may have printing rules or type or other printing characters thereon, as desired.

The strips 42 may have printing rules 42' or these printing rules may be omitted, as before, in which case the strips 42 will serve as binder strips only for the slugs 40.

Where the slugs 9 are provided with printing rules 12 in Figs. 1 to 5 and 8, or where the slugs 40 are provided with printing rules 40' in Figs. 6, 7 and 10, the grooves 20 (Fig. 8) continue through these rules at 20' and are of a formation conforming with the formation of the projecting rules on the printing slugs.

In the embodiment of Fig. 11, the slugs 45 are provided with printing characters 46 shown in the form of type letters, although this may vary, and in this case the strips 48 serve as tie strips as in the previous embodiments and seat upon the rail surfaces of the carrier, as before. In this case, the outer edges of the strips 48 are not provided with projecting printing rules, but terminate inwardly of the printing line so that they will not engage the paper or other material with which the printing line cooperates, nor perform any printing function, but will serve merely as tie elements.

In the embodiment of Fig. 12, I have shown the invention in connection with a flat base plate for use with flat bed presses. This flat base plate is indicated at 50 and is provided with under-cut channels 51 corresponding with the channels 7 of Figs. 1 and 2. The slugs 52 are similar to the slugs of the previous embodiment and are mounted in the channels or chases 51 with their outer flanged heads 53 seating upon the outer surface of the carrier 50.

The strips 54 are applied in the same manner and may be varied as pointed out in connection with the previous embodiment, the only difference being that the strips 54 are, in this case, straight with their bases seating upon the outer surface of the carrier 50. They are interlocked with the slugs 52 in the manner pointed out in connection with the previous embodiment and they may be provided with printing rules 54', or these printing rules 54' may be omitted. The slugs 52 are shown as spaced apart by skipping chases 51, and the slugs may be provided with printing rules 56, as shown, or with printing characters or the printing rules and printing characters may be omitted and the slugs 52 used merely for supporting and binding the rules 54' together. As before, the interlocking of the slugs 52 and strips 54

binds these elements into a unitary assembly which may be conveniently removed and replaced as a unit and, at the same time, the assembly is flexible, in that the parts are all separable and may be removed and replaced with others.

In Fig. 13 I have provided for applying horizontal rules without skipping spaces between the slugs. In this case the slugs are indicated at 60 and these slugs interlock with and are bound together by the strip 62, which may have a printing rule or may be formed without this rule, as before. Likewise, the slugs 60 may be provided with printing characters, or these may be omitted. In order to apply the horizontal rule indicated at 63, the flanged heads 64 of the slugs 60 have complementary tapered edges forming generally V-shaped grooves 65 into which the rule 63 is applied by inserting it endwise.

This rule 63 is shown as provided with a projecting rule edge 63' for printing cooperation with the paper or other material. The base 66 of the rule 63 is preferably flat and preferably seats upon the outer rail surface of the carrier when the assembled slugs 60 and strips 62 are applied thereto.

In the embodiment of Fig. 14 I have provided short separate or individual grooved blocks 70 for mounting in the chases of the drum or in the chases of the flat plate carrier in the manner of the type slugs or type lines of the previous embodiment. These individual blocks 70 are provided with grooves 72 similar to those previously described for receiving and interlocking with the printing rule and binder strips 74. In this case, as before, the grooves 72 will preferably extend inwardly to or inwardly beyond the surface of the carrier so that the strips 74 will rest and find support upon the surface of the carrier or the outer rail surface thereof. The individual grooved blocks 70 in this case are preferably blank blocks for the sole purpose of holding the rule strips 74, but these blocks 70 might be provided with printing characters if desired.

As shown in Fig. 1, the chases between the drum rails 6 may be closed at one end of the drum by a circumferentially extending flange or end ring 80. This end ring may be of the usual known character, and it is to be understood that in a flat plate carrier the ends of the chases may be closed, as desired.

I do not intend to be limited to the precise details shown or described.

I claim:—

1. In combination, a carrier, a slug adapted to be interlocked with said carrier and a cross strip interlocking with the slug and seating upon said carrier.

2. In combination, a carrier, a slug less than "type high" adapted to be interlocked with said carrier, and a cross strip interlock-

ing with said slug and seating upon said carrier.

3. In combination, a carrier, a unitary slug line adapted to be interlocked with said carrier, and a plurality of cross strips interlocking with said slug line and seating upon said carrier. 70

4. In combination, a carrier, a plurality of slugs adapted to be interlocked with said carrier, and a cross strip interlocking with 75 said slugs and seating upon the carrier.

5. In combination, a carrier, a plurality of slugs adapted to be interlocked with said carrier, and a plurality of cross strips interlocking with said slugs and seating upon said carrier. 80

6. In combination, a plurality of slugs each comprising a unitary line of a length equal to the combined length of a plurality of individual type slugs and each less than "type 85 high", said slugs having retention means for interlocking the slugs with a carrier, and tie strips interlocking transversely with said slugs and adapted to seat upon the carrier, the interlocking of said strips with said slugs joining said slugs and strips together into a unitary assembly adapted for attachment to and removal from said carrier as a unit. 90

7. In combination, a plurality of slugs each comprising a unitary line of a length equal to the combined length of a plurality of individual type and each less than "type high", said slugs having retention means for interlocking the slugs with a carrier, tie strips 95 interlocking transversely with said slugs and adapted to seat upon the carrier, the interlocking of said strips with said slugs joining said slugs and strips together into a unitary assembly adapted for attachment to and removal from said carrier as a unit, and printing means on said slugs for printing cooperation with the paper or other material. 100

8. In combination, a plurality of slugs each comprising a unitary line of a length equal to the combined length of a plurality of individual type slugs and each less than "type 110 high", said slugs having retention means for interlocking the slugs with a carrier, tie strips interlocking transversely with said slugs and adapted to seat upon the carrier, the interlocking of said strips with said slugs joining said slugs and strips together into a unitary 115 assembly adapted for attachment to and removal from said carrier as a unit, and printing means on said tie strips. 120

9. In combination, a plurality of slugs each comprising a unitary line of a length equal to the combined length of a plurality of individual type slugs and each less than "type high", said slugs having retention means for interlocking the slugs with a carrier, tie strips 125 interlocking transversely with said slugs and adapted to seat upon the carrier, the interlocking of said strips with said slugs joining said slugs and strips together into a unitary 130

assembly adapted for attachment to and removal from said carrier as a unit, printing means on said slugs for printing cooperation with the paper or other material, and printing rule edges on said tie strips.

10. In combination, a carrier, a slug adapted to be interlocked with said carrier, said slug having a flanged head, said head having a groove extending to the depth of said head and a cross strip engaged in said groove and adapted to seat upon said carrier when the slug and strip are arranged thereon.

11. In combination, a carrier, a plurality of slugs adapted to be interlocked with said carrier, said slugs having flanged heads, said heads having grooves extending through the depths of said heads, and a plurality of cross strips engaged in said grooves and adapted to seat upon said carrier when the slugs and cross strips are arranged thereon.

12. As an article of manufacture, a slug having a head flange and a base flange with a connection between said flanges, said head flange having a groove extending transversely therethrough and to the depth of said head flange.

13. As an article of manufacture, a unitary slug line of a length equal to the combined length of a plurality of individual type slugs, said slug having a head flange and a base flange with a connection between said head and base flanges, said head flange having a plurality of grooves extending transversely therethrough and to the depth of said head flange.

14. In combination, a plurality of slugs less than "type high" and each comprising a unitary line of a length equal to the combined length of a plurality of individual type slugs, said slugs being spaced apart and having transverse grooves and tie strips extending transversely through and interlocking with said grooves, the interlocking of said strips with said slugs joining said strips and slugs together into a unitary assembly adapted for attachment to and removal from a carrier as a unit.

15. In combination, a plurality of slugs each comprising a unitary line of a length equal to the combined lengths of a plurality of individual type slugs and each less than "type high", said slugs having retention means for interlocking the slugs with a chased carrier, and tie strips extending transversely of said slugs and engaged therewith, said strips joining said slugs together into a unitary assembly adapted for attachment to and removal from said carrier as a unit and seating upon the chased surface of the carrier when the slug and tie strip assembly is in place thereon.

16. In combination, a plurality of slugs each comprising a unitary line of a length equal to the combined lengths of a plurality

of individual type and each less than "type high", said slugs having retention means for interlocking the slugs with a chased carrier, tie strips extending transversely of said slugs and engaged therewith, said strips joining said slugs together into a unitary assembly adapted for attachment to and removal from said carrier as a unit and the tie strips having relatively tight fit with the slugs for restraining relative displacement of the slugs along the strips.

17. In combination, a carrier, a plurality of slugs adapted to be interlocked with said carrier, said slugs having flanged heads having transverse grooves through the depths of said heads, said grooves being formed to provide opposed retaining faces, and a plurality of cross strips engaged in said grooves and provided with complementary faces cooperating with said retaining faces for interlocking engagement with said slugs to the depths of said heads.

18. In combination, a carrier, a plurality of slugs adapted to be interlocked with said carrier, said slugs having flanged heads having transverse grooves through the depths of said heads, said grooves being formed to provide opposed retaining faces, and a plurality of cross strips engaged in said grooves and provided with complementary faces cooperating with said retaining faces for interlocking engagement with said slugs to the depths of said heads, said strips having bases adapted to seat upon said carrier in the assembled relation of said slugs, strips and carrier.

19. In combination, a carrier, a plurality of slugs adapted to be interlocked with said carrier, said slugs having flanged heads having transverse grooves through the depths of said heads, said grooves being formed to provide opposed retaining faces, and providing smaller interruptions of the surfaces of slugs than in the remainder of said heads, and a plurality of cross strips engaged in said grooves and having complementary faces tightly cooperating with the retaining faces for interlocking engagement with said slugs to the depths of said heads and through the interruptions.

20. In combination, a carrier having a plurality of chases, a plurality of slugs having retention means cooperating with said chases for interlocking the slugs with the carrier and having flanged heads extending outwardly beyond the carrier, said heads having transverse grooves therein, and tie strips extending through said grooves and interlocking with said heads to the depths of the heads whereby said slugs and strips are rigidly joined together for attachment to or detachment from the carrier as a unit, said strips being adapted to seat upon the surface of the carrier in attached position.

21. In combination, a carrier having a plu-

rality of chases, a plurality of slugs having retention means cooperating with said chases for interlocking the slugs with the carrier and having flanged heads extending outwardly beyond the carrier, said heads having transverse grooves therein, said grooves being defined by opposed retaining faces, and a tie strip engaged in said grooves and provided with complementary faces cooperating with said retaining faces for interlocking engagement with said slugs to the depths of said heads whereby said slugs and strip are rigidly joined together in the assembled relation thereof for attachment to or detachment from said carrier as a unit, the strip being adapted to seat upon the surface of the carrier in attached position.

In witness whereof, I hereunto subscribe my name this 3d day of December, 1929.
